ALBERT BERTRAM WILLETT, OF SACRAMENTO, CALIFORNIA

AEROPLANE-CONTROL APPARATUS

Application filed July 22, 1929. Serial No. 379,891.

This invention relates generally to apparatus intended to be used in conjunction with an aeroplane in order to secure automatic or semi-automatic control of the plane in flight.

5 It is a general object of this invention to devise apparatus of the above character which can be readily incorporated with aeroplanes of standard construction, and which will be relatively light and simple to operate.

10 It is a further object of this invention to devise a novel frame adapted to be mounted upon an aeroplane, and adapted to carry parts of an aeroplane control system.

15 Further objects of the invention will appear from the following description in which I have set forth the preferred embodiment of my invention. It is to be understood that the appended claims are to be accorded a 20 range of equivalents consistent with the state of the prior art.

Referring to the drawing:

Figure 1 is a plan view illustrating apparatus incorporating my invention.

25 Fig. 2 is a cross sectional view taken along the line 2—2 of Fig. 1.

Fig. 3 is a cross sectional view in side elevation, illustrating the detailed construction of the preferred embodiment of my device.

30 In my copending application filed April 2, 1929, Ser. No. 352,029, I have disclosed an apparatus for use in conjunction with an aeroplane, in order to secure automatic control of the aeroplane stabilizing surfaces.

35 Provision is made for controlling the apparatus manually, to enable the aeroplane to take off properly and make landings, and also to bank properly in making turns. In some respects the subject matter of the present application is a continuation in part and also an improvement of the apparatus of that case.

40 When my apparatus is installed in an aeroplane, it utilizes forces produced by suitable means, as by gravity upon a suitable weight, for operating the stabilizing surfaces of the aeroplane, thus producing automatic or semi-automatic stability. Referring to the apparatus illustrated in the drawing I have shown a frame 10 which is pref-

erably disposed within the fuselage of an aeroplane. This frame is preferably triangular in shape, and in practice can be formed by side bars 11, having their ends connected together by an end bar 12. For the sake of lightness these bars are preferably hollow or tubular. For mounting the frame upon the aeroplane fuselage, brackets 13 are shown fixed to the end portions of end bar 12, and these brackets are supported by a lateral bar 14, which is normally horizontal and positioned laterally of the fuselage. Suitable clamps 15 are shown fixed to the ends of bar 14, and these clamps are adapted to engage upright members 17 of the aeroplane fuselage.

For a reason which will be presently explained, the frame is preferably capable of being shifted laterally along the rod 14 from a neutral position and against spring tension. In order to permit this movement, it is convenient to slidably mount brackets 13 upon a sleeve 16, which in turn is slidably mounted upon rod 14. One bracket 13 is adapted to engage a stop 18, this stop being adjustably threaded to sleeve 16. Sleeve 16 is urged in one direction on rod 14, by means of a compression spring 21, one end of this spring being seated upon a washer 22, the washer being slidable upon rod 14 and normally pressed against one end of sleeve 16. The other end of spring 21 is seated upon a washer 23, which engages the relatively fixed clamp 15. The frame is urged in the opposite direction upon sleeve 16, by means of compression spring 24. One end of this spring 24 is seated upon a washer 26, which in turn presses against one of the brackets 13, and the other end of spring 24 is seated upon member 27. Member 27 is threaded upon sleeve 16, so as to permit adjustment of the tension of spring 24. It is evident that with this mounting for the frame, if the frame is moved in one direction along rod 14, sleeve 16 slides upon rod 14, and spring 21 is compressed. At the same time spring 24 moves bodily with sleeve 16. When the frame is shifted in the opposite direction from its neutral position, sleeve 16 remains stationary, brackets 13 slide upon this sleeve, and

spring 24 is compressed. Therefore springs 21 and 24 both act to normally urge the frame toward a neutral position, and movements of the frame laterally of the fuselage, or in the direction of rod 14, tends to compress one or the other of springs 21 or 24.

The frame 10 supports certain parts of a control apparatus, and in the preferred embodiment of the invention these parts include 10 a lever arm 31 which is associated with the universal joint 32. Arm 31 is moved by forces created according to the position of the aeroplane in flight, as for example by means of gravity acting upon a weight 33. 15 Universal joint 32 can consist of an outer ring 34 and an inner ring 36, which are pivotally connected along a horizontal axis, by means of pivot pins 37. Ring 36 in turn is journaled upon a collar 38, as by means of ball 20 bearings 39. The journaling of inner ring 36 upon collar 38 is about a horizontal axis substantially at right angles to the pivotal axis of pins 37. In order to support the universal joint 32 upon the frame 10, a central 25 frame rod or member 41 is provided, one end of this member being connected to the medial portion of rod 12, while the other end is connected to the junction between the two rods 11. As the frame is normally installed in an 30 aeroplane, member 41 is in a substantially horizontal position and extends in the direction of normal flight. Collar 38 is slidably disposed upon member 41, as shown in Fig. 3, and relative rotation between the collar 35 and member 41 is prevented by providing a key or setscrew 42, projecting into a groove 43 provided in member 41.

In order to provide means whereby the collar 38 and the universal joint 32 can be 40 shifted longitudinally of the aeroplane, or along the member 41, I have shown suitable means consisting of a gear 44, this gear being retained within a suitable housing 46. Gear 44 is fixed to a suitable rotatable control shaft 45 47, this shaft extending substantially laterally of the frame 10, and laterally of the aeroplane. Gear 44 is adapted to operably engage with another gear 48, this latter gear being also journaled in housing 46 on an axis 50 at substantially 90° to the axis of shaft 47. Gear 48 is internally threaded so as to engage a threaded rod 49. Collar 38 carries a depending member 51, to which one end of threaded rod 49 is secured. For manual rotation of control shaft 47, I have shown a suitable hand wheel 52. It is evident that upon rotation of the control shaft 47, gear 48 is rotated to project or retract threaded rod 49, and thus shift the position of collar 38 55 upon member 41. In order to provide additional support means for the frame 10, I have shown a support rod 53, one end of which is provided with a pivotal or ball and socket connection 54 with the lower portion of gear 60 housing 46. The lower end of this rod is 65

provided with a pivotal or ball and socket connection 56, with a fixed support 57. This fixed support corresponds to some fixed part of the aeroplane fuselage.

For making connections between lever arm 31 and the surfaces of the aeroplane which control the aeroplane stability, I have shown an arm 58 fixed to the upper portion of ring 34. This arm has a fork 59 provided with a pivotal connection to a socket 60, which in turn carries an L-lever or arm 61. Pivotal connection between fork 59 and socket 60 can be formed by pivot pins 62, to permit lever 61 to swing about a horizontal axis. A socket 63 is carried by the outer end of lever 61 and this socket is adapted to fit over the upper end of the aeroplane control stick, such as is commonly used in aeroplanes of standard construction.

To explain the mode of operation of my apparatus, it will be presumed that the aeroplane is in ordinary flight and that the socket 63 has been positioned upon the upper end of the aeroplane control stick. If the aeroplane tends to nose downwardly, weight 33 swings forwardly, and lever 61 is moved backwardly to pull back the control stick 63, thus raising the elevation rudder a sufficient amount to bring the aeroplane back to level keel. Similarly if the aeroplane noses upwardly, weight 33 swings backwardly and the control stick is thus moved forwardly to depress the elevation rudder. If the aeroplane shifts to one side, weight 33 also swings to that side, and lever 61 is moved to force stick 63 in a direction to operate the ailerons or the other surfaces which control lateral stability, thus bringing the aeroplane back to horizontal position. If the pilot desires to descend under automatic control, hand wheel 52 is operated to shift collar 38 and the universal joint 32 forwardly, thus moving the control stick to depress the elevating rudder while lever arm 31 still remains in a substantially vertical position. Likewise the pilot can take off under automatic control by operating hand wheel to shift the universal joint 32 rearwardly to raise the elevating rudder.

In making turns, weight 33 in some instances may not respond quickly enough to bank the plane to the proper angle. In this event the pilot can bank the plane quickly by applying manual force to frame 10, to shift this frame laterally upon the supporting rod 14. Such movement of the frame has the effect of forcing over the control stick irrespective of the weight 33. After the turn has been commenced, it can be completed under control of weight 33, by releasing the frame 10 and thus permitting it to return to neutral position.

I claim:

1. In an aeroplane control, a frame adapted to be secured to a relatively fixed support, a lever arm adapted to be moved laterally in

any direction, a universal joint connected to said arm, said joint including a collar, a member carried by the frame slidably extended thru said collar, and means for shifting the position of said collar on said member.

5. 2. In an aeroplane control, a frame adapted to be secured to a relatively fixed support, a lever arm, automatic stability means connected to said arm, a universal joint connected to said arm, said joint including a collar, a member incorporated in said frame and slidably extended thru said collar, a control shaft rotatably journaled to said frame, and means connecting said control shaft to said collar for shifting the position of the collar and said shaft relative to the frame upon rotation of the shaft.

10. 3. In an aeroplane control, a frame, support means for securing one portion of said frame to an aeroplane fuselage whereby said frame can be shifted laterally, and a single point support for supporting another portion of said frame.

15. 4. In an aeroplane control, a frame, support means for securing one portion of said frame to an aeroplane fuselage, said support means permitting lateral shifting of the frame, stability control means carried by said frame, a support rod having a pivotal connection with another portion of the frame, and means for pivotally connecting said rod to an aeroplane fuselage.

20. 5. In an aeroplane control, a substantially triangular frame, means for slidably supporting one side of said frame, means for supporting the apex of the frame which is remote from said side, and aeroplane control means carried by said frame.

25. 6. In an aeroplane control, a substantially triangular frame, means for supporting said frame adjacent the apexes thereof, a universal joint movably supported by the frame within the sides thereof, and a stability controlling arm secured to said joint.

30. 45. In testimony whereof, I have hereunto set my hand.

ALBERT BERTRAM WILLETT.
